Primary Examiner — Jeffrey D Asch*Assistant Examiner* — Natalya M Rapundalo(74) *Attorney, Agent, or Firm* — NSIP Law(57) **CLAIM**

I claim the ornamental design for a microwave, as shown and described.

DESCRIPTION

FIG. 1 is a front perspective view of a microwave showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a cross-sectional view taken through line 8-8 of FIG. 6; and,

FIG. 9 is an enlarged view of the portion 9 in FIG. 1.

The evenly dashed broken lines in the figures depict portions of the microwave which form no part of the claimed design. The dot-dot-dash broken lines encircling enlargement portions of the claimed design form no part of the claimed design.
